UNITED STATES PATENT OFFICE.

LOUIS FISCHER, OF PHILADELPHIA, PENNSYLVANIA, ASSIGNOR TO WRIGHT'S AUTOMATIC TOBACCO PACKING MACHINE COMPANY, OF DURHAM, NORTH CAROLINA, A CORPORATION OF WEST VIRGINIA.

PACKAGING MACHINE.

Application filed February 2, 1927. Serial No. 165,410.

The present invention relates to improvements in packaging apparatus and more particularly to machines for packing tobacco or other materials of a granular or generally similar nature into wrappers to form the same into packages.

The primary object of the invention is to provide a machine of this class which is capable of rapidly and economically producing packages of tobacco or other material which are substantially solid and firm and wherein the wrapper is so formed and closed as to effectually prevent sifting or leakage of tobacco or other contents therefrom during shipment, storage or handling. With this general object in view, the invention provides novel and improved means for partially forming the wrapper and presenting it to the packer or other means which introduces the tobacco or other contents therein whereby these operations may be performed quickly without spilling and consequent loss of tobacco; means for folding the sides of the filled wrapper to close it whereby these operations may not only be performed quickly and with certainty but the wrapper is drawn tightly around the tobacco or other contents, thus producing a substantially solid and firm package; means for folding the ends of the wrapper and retaining the ends in folded condition in a manner which closes the ends of the wrapper and avoids spilling of the tobacco or other contents; means for indenting or countersinking the folded ends of the wrapper while the latter and its contents are confined against lateral expansion or distortion, whereby the tobacco contained in the package is compressed or densified, thus imparting solidity and firmness to the package and also imparting a permanent set to the end folds of the wrapper which tends to retain these end folds in folded or end-closing position, thereby precluding accidental opening of either end of the package and preventing leakage of the tobacco or other contents therefrom; and the invention provides other means as will hereinafter appear which facilitate the foregoing operations and such other operations as may be employed to complete the making of packages possessing the advantageous characteristics hereinbefore referred to.

To these and other ends, the invention

consists in certain improvements and combinations and arrangements of parts all as will be hereinafter more fully described, the features of novelty being pointed out particularly in the claims at the end of the specification.

In the accompanying drawings:—

Fig. 1 is a side elevation of a packaging machine constructed in accordance with the present invention, a portion of the operating mechanism being broken away for clearness;

Fig. 2 is an end elevation of the machine shown in Fig. 1 as viewed from the left in that figure;

Fig. 18 is a view similar to Figs. 15 to 17 15 inclusive, this view showing the tucker in position to effect the final folding of the wrapper around the package;

Fig. 19 is an end view and Fig. 20 is a 20 side view of the folders which fold and close the end of the wrapper, a portion of the mold wheel and the operating means for the end folders being also shown, the end folders being shown in retracted position;

Fig. 21 is a view similar to Fig. 20 but 25 showing the side end folders in position to fold the side ends of the wrapper;

Fig. 22 is a view similar to Fig. 21 but 30 showing the side end folders retracted and the last end folder in position to make the last end fold;

Fig. 23 represents a cross section through Fig. 20 on the line 23—23 and looking downwardly;

Fig. 24 is an elevation of the mold wheel 35 guard, and the countersinks, the latter being retracted;

Fig. 25 is a side elevation of a portion of the mold wheel showing the mold wheel guard cooperative therewith;

40 Fig. 26 is a view of a portion of the structure shown in Fig. 24 showing the countersinks forced inwardly into the ends of a package;

Fig. 27 represents on an enlarged scale a 45 section taken through one of the countersinks, this view also showing the adjacent portion of the mold wheel;

Fig. 28 is a side elevation of the upper 50 portion of the mold wheel and showing a portion of the cam which operates the bottom end folders;

Fig. 29 represents a section through the mold wheel on the line 29—29 of Fig. 28 and looking toward the left;

55 Fig. 30 represents a fragmentary sectional view through the periphery of the mold wheel showing one of the pivoted mold lids;

Fig. 31 represents a fragmentary section 60 through the mold wheel on the line 31—31 of Fig. 29;

Fig. 32 is a diagrammatic view showing the manner in which the wrapper is carried into the mold by the nipping plunger;

Fig. 33 shows diagrammatically the bottom 65 folds made in the wrapper;

Fig. 34 shows diagrammatically the first top fold made in the wrapper;

Fig. 35 shows diagrammatically the second top fold made in the wrapper;

Fig. 36 shows diagrammatically the last 70 top fold made in the wrapper;

Fig. 37 shows diagrammatically the side end folds made in the wrapper, and

Fig. 38 shows diagrammatically the top 75 end fold of the wrapper.

Similar parts are designated by the same reference characters in the different views.

The present invention is applicable generally to packaging machines of the kinds in which a wrapper, composed of a label, sheet 80 of paper or other suitable flexible material, is folded about an article or a charge of material to form a package, although the invention is particularly applicable to the packaging of loose or granular material 85 such as tobacco and the like. The preferred embodiment of the invention is herein shown and described as applied to the packaging of tobacco or similar loose material, but it is to be understood that the invention is not 90 restricted to the precise construction shown as equivalent constructions are contemplated and such would be included within the scope of the claims at the end of the specification.

In the embodiment of the invention shown, the various mechanisms and other operating means are supported by a suitable frame which may comprise upright side members 1 and a connecting supporting base 2. The various mechanisms of the machine are actuated or driven, in properly timed relation, from a main shaft 3 which is journaled in and extends through the side members of the frame, this shaft being driven by belt pulleys 4 or any other suitable means. 95

The invention, in the instance shown, is applied to a packaging machine of the type shown and described in U. S. Patent No. 586,076 granted July 6, 1897, to W. Rose, it employing a rotary mold wheel 5 which has a 110 series of pockets or molds 6 formed in and spaced circumferentially of its periphery, these pockets being adapted to successively receive a sheet of paper or the like which is to form the wrapper, a charge of material 115 which is introduced or packed into the mold and folding mechanisms to operate on the wrapper to complete the folding thereof and thus form a complete package. The mold wheel is intermittently rotated to bring the 120 pockets therein successively into the different operative positions, the mold wheel in the present instance being keyed or otherwise fixed on the mold wheel shaft 7 which latter is journaled in the sides of the frame, one end of this shaft being connected by a Geneva movement or other suitable mechanism to the main shaft 3 whereby the mold wheel will receive such intermittent advancing movements during operation of the ma- 125

130

chine. In the present instance a Geneva movement is employed for this purpose which comprises a Geneva disk 8 which is fixed on the mold wheel shaft 7, a wheel 9 carrying a pin 10 which successively engages the radial slots 11 in the periphery of the Geneva disk, and a locking pin 12 which is moved successively into the slots 11 in the Geneva disk to lock the mold wheel in each of its operative positions, the locking and unlocking movements of the pin 12 being controlled by a weight 13 on a lever 14 which carries the pin 12 and is pivoted on the main frame at 15, the rocking movements of the lever 14 to effect locking and unlocking of the mold wheel being controlled by a cam 16 on the main shaft 3 which cooperates with a roller 16^a carried by an arm of the lever 14. The Geneva movement just described or any equivalent of it may be employed to effect intermittent advancing movements of the mold wheel to bring the circumferentially spaced pockets therein successively into the different operative positions and to lock the mold wheel during the intervening periods.

Each pocket of the mold wheel, according to the present invention, has a hinged or movable lid 17 which forms one of the side walls thereof, each of these lids in the present instance being carried by a lever 18 which is pivoted intermediately of its length to the mold wheel by the pivot pin 19 and the inner end of each lever has a treadle or actuating projection 20 thereon which is arranged to be engaged and pressed inwardly or toward the center of the mold wheel, each time the mold wheel reaches a predetermined position in its rotation, by a pin 21 carried on one end of a lever 22. This lever is pivoted on the main frame at 23 and has a roller 24 on its opposite end which rides against a cam 25, the latter being fixed on a shaft 26, and the roller 24 is held in engagement with this cam by a tension spring 27 which acts on the lever. Each successive advance of the mold wheel will bring one of the projections 20 into position to be engaged by the pin 21, and when the cam 25 reaches a predetermined point in its rotation, the depressed or low portion of this cam will reach the roller 24 and the spring 27 is then permitted to act to force the pin 21 against the projection 20 and thereby swing the lid of the respective mold into open position. A compression spring 28 may be arranged to act on the lid to hold it in closed position except when the pin 21 is permitted to act to open the lid, it being understood that the strength of the spring 27 is superior to that of each of the springs 28. Each pocket of the mold wheel is also preferably provided with inturned lips 29 which overhang the respective mold pockets, for a purpose which will hereinafter appear.

The paper or other flexible sheets or labels which are to form the wrappers of the pack-

ages may be supplied successively to the mold wheel in different ways, but it is preferable to supply the wrappers by a feed trough 30 which is of a width corresponding to that of the wrappers and contains in its bottom the upper stretch of a conveyer chain 31 which has hooks or projections 32 located thereon at appropriate intervals whereby they will engage the rear edges of the wrappers and thus advance them edgewise through the feed trough while the wrappers lie flatwise on the bottom thereof. The conveyer chain 31, which may be endless, is preferably driven continuously by the shaft 33 which has a sprocket wheel 34 thereon over which the end of the conveyer chain adjacent to the mold wheel passes, it being understood that the opposite end of the conveyer chain may pass over an idler sprocket at the opposite or outer end of the feed trough. The shaft 33 is driven continuously at a suitable speed by a gear 35 fixed thereon and meshing with a gear 36 fixed on the shaft 26, and the latter shaft is driven continuously by a sprocket wheel 37 which is fixed on its outer end, this sprocket wheel cooperating with a chain 38 which cooperates with the sprocket teeth 39 which may be formed on the periphery of the wheel 9, the latter being fixed on the continuously running main shaft 3. The upper stretch of the chain 38 may be guided and the tension of the chain may be adjusted by an idler sprocket wheel 40 which is carried by an arm 41 the hub of which is clamped on the hub of the mold wheel bearing so that the idler sprocket wheel 40 may bear on the upper side of this stretch of the chain.

Extending inwardly from the end of the feed trough 30 adjacent to the mold wheel are a pair of wrapper supporting arms 42. These arms are spaced apart sufficiently to straddle or pass downwardly at the opposite sides of the mold wheel. These arms normally form continuations of the bottom of the feed trough 30, the upper edges of these arms lying in the same plane with the wrapper supporting surface of the feed trough as will be seen from Fig. 4, and the ends of the wrapper supporting arms are turned upwardly to form stops 43 which arrest the advance of the wrappers toward the mold wheel and serve as gages to properly position the wrappers relatively to the respective pockets in the mold wheel. While these wrapper supporting arms 42 occupy positions in substantial alinement with the wrapper feed trough during the feeding of a wrapper to such arms, the latter may be lowered or depressed in order to transfer the wrapper to the mold wheel and to avoid interference between these arms and the devices which introduce the wrapper into the mold pocket. In the construction shown, for example, these arms are fixed to a sleeve 44 which is loosely mounted on a shaft 44 and the sleeve 44 carries a roller 139

45 which rides against a cam 46 and is held in engagement with this cam by the weight of the wrapper supporting arms. The cam 46 is fixed to the continuously running shaft 26 and the cam is appropriately shaped to raise and lower the wrapper supporting arms at appropriate intervals.

50 Adjacent to the discharge end of the conveyer chain 31 are mounted a pair of wrapper registering fingers (Figs. 4, 5, 6 and 7) which serve to finally advance the wrapper against the stops 43 on the ends of the wrapper supporting arms 42 and thereby register the wrappers. As shown, these registering fingers 55 designated 47 are fixed on a shaft 48 which is mounted to rock in the opposite sides of the feed trough 30, these fingers being arranged to swing toward the bottom of the feed trough and into position behind the rear 55 edge of a wrapper advanced by the conveyer chain, the final portion of the swinging movement of these fingers serving to bring the forward edge of the wrapper evenly against the stops 43 on the wrapper supporting arms. At other times these fingers will occupy the relatively elevated and retracted position shown in Figures 4, 5 and 6. These fingers then clear the bottom of the feed trough to permit a wrapper to be fed into a 60 position in front of them. These registering fingers may be actuated at appropriate intervals by any suitable means, a cam 49 being provided for this purpose in the present instance which is fixed to a sprocket wheel 50 which is mounted loosely on the shaft 33, this sprocket wheel being engaged by a chain 51 which is driven by a sprocket wheel 52, the latter being fixed on the shaft 26. A bell-crank lever 53 is fixed on one end of the shaft 48 and one arm of this lever is pivotally connected to a fork 54 which straddles the shaft 33, the fork carrying a roller 55 which rides on the cam 49. A tension spring 56 is connected to the other arm of the bell-crank 65 lever, this spring acting to hold the roller 55 in contact with the cam 49. It will be understood that when the roller 55 engages the low part of the cam 49 the registering fingers 47 will occupy their upper retracted position, and when the roller 55 rides up on the high part of the cam, the registering fingers are swung downwardly and forwardly to bring them into engagement with a wrapper and to register the wrapper with the stops 43 on the 70 inner ends of the wrapper supporting arms 42.

75 The upper wrapper supporting surface of the arms 42, when the latter are elevated, is level with the upper portion of the mold wheel immediately above one of the mold pockets therein, when the mold wheel is at rest in one of its operative positions, and the stops 43 on the ends of the arms 42 project above the periphery of the mold wheel, and in consequence when a wrapper is fed along

these arms 42 and out against the stops 43, the forward edge of the wrapper is so guided that it will not catch upon the gap in the mold wheel formed by the mold pocket, and the forward portion of the wrapper will be 70 caused to overlie the periphery of the mold wheel. Preferably a guard 57 is provided opposite to the periphery of the mold wheel to prevent deflection of the forward end of the wrapper while it is being advanced to the 75 stops 43, thus insuring engagement of the wrapper with these stops. The guard may, as shown, be formed of a plurality of bars 58 which are supported immovably by cross rods 59 which bridge the sides of the feed 80 trough, the lower edges of these bars being preferably curved to conform with the curvature of the periphery of the mold wheel.

Above the feed trough and working in the same vertical planes with the respective 85 wrapper supporting arms 42 is mounted a pair of grippers 60 which operate to carry the registered wrapper into the mold pocket while preventing displacement of the wrapper. These grippers are of a width which corresponds substantially with the circumferential dimension of the mold wheel pocket, the marginal portions of the wrapper which are to form the end flaps thereof being foldable about these grippers when the wrapper is folded to form the bottom and two opposite sides thereof. The grippers occupy positions above the bottom of the feed trough and above the upper edges of the respective arms 42 until a wrapper has been fed beneath them and into position on the supporting arms 42 after which the grippers descend causing them to momentarily grip the wrapper between their lower corners and the upper edges of the arms 42, as is shown in 90 Fig. 4, whereupon the arms 42 begin to descend while the grippers continue their descent, and thus remain in wrapper gripping engagement therewith, the descent of the arms 42 while the grippers are in engagement 95 therewith causing the wrapper thereon to be lowered on to the mold wheel and the grippers act to carry the intermediate portion of the wrapper into the mold pocket as shown in Fig. 6, after which the descent of 100 the grippers 60 ceases but the arms 42 descend sufficiently to disengage from the wrapper, as is shown in this figure. A nipping plunger 62 is also provided, it occupying a position between the grippers and having 105 a shape which corresponds substantially with the shape of the mold pocket. The nipping plunger is arranged to engage the portion of the wrapper which lies between the grippers and the nipping plunger has a movement which carries it into the mold pocket. As the nipping plunger enters the mold 110 pocket it forces the intermediate portion of the wrapper into the pocket, the portion of the wrapper beneath the plunger being carried 115 120 125 130

ried to the bottom of the pocket and the adjacent portions of the wrapper being folded so that they lie against the opposite radial sides of the pocket. One edge of the nipping 5 plunger has a lip 63 thereon which overhangs its adjacent side. This lip is arranged to assume a position immediately above and in close proximity to the forward overhanging lip 29 of the mold pocket when the nipping 10 plunger has fully entered the mold pocket. This lip on the plunger thereby co-acts with this lip 29 on the mold wheel to nip and sharply bend the wrapper over the adjacent lip 29. This nipping operation is shown in Figure 15 6, the nipping plunger being then fully entered in the mold pocket and at this time the forward edges of the grippers 60 are on substantially the same level with the forward or lower surface of the nipping plunger. 20 The wrapper designated α is shown in this figure as folded immediately against the bottom and two radial sides of the mold pocket, and the forward and rear ends of the wrapper are shown projecting from the forward and 25 rear sides of the mold pocket. The nipping or sharp folding of the wrapper between the nipping lips 29 and 63 is also shown in this figure. After the wrapper has been introduced into the mold pocket and folded there- 30 in in the manner described, the grippers 60 and the nipping plunger 62 are elevated, they being thereby retracted from the mold pocket and returned to positions above the bottom of the feed trough so that another wrapper 35 may be advanced along the feed trough without interference from the grippers or plunger, the descent and ascent of the grippers and plunger referred to taking place while the mold wheel is at rest 40 in one of its operative positions. After the mold wheel has advanced a step, the wrapper supporting arms 42 are raised through the action of the cam 46, these arms being thereby returned to their former po- 45 sition in alinement with the bottom of the feed trough so that they will be in position to receive the next wrapper which is being advanced along it.

The grippers 60 and plunger 62 may be 50 operated at appropriate intervals by different means. As shown, the grippers 60 are fixed to an arm 64 which is provided with a hub 65 the latter being loosely mounted on the shaft 44, the hub 65 carrying a roller 66 which is held by a spring 67 against a suitably shaped cam 68, the latter being fixed on the shaft 26. The plunger 62 in the present instance is carried by an arm 69 which has a hub 70 which is loosely mounted on the shaft 55 44, this hub carrying a roller 71 which is held by a spring 72 against a suitably shaped cam 73, the latter being fixed on the shaft 26. It will be understood that the cams 68 and 73 are so shaped as to cause the grippers 60 and

plunger 62 to advance and recede substantial- 65 ly as above described.

The mold wheel is provided with pairs of end folders 74, there being a pair of these end folders for each mold pocket in the wheel, and these folders are mounted to operate radially outwardly past the ends of the respective mold pockets to make the bottom or first end folds in the wrapper. These end folders may be mounted as shown in Figures 70 28, 29 and 30 wherein each pair of these 75 folders are fixed to a slide 75 which is reciprocable in a radial slot 76 in the mold wheel, and the movements of the folders 74 in a direction radially of the mold wheel are controlled by a cam 77 the groove 78 in which 80 receives and forms a track for rollers 79 which are connected to and project radially from the respective slides 75. The major portion 78^a of the cam groove is concentric with the mold wheel shaft 7 and moreover 85 this portion of the cam groove is nearest the center of the mold wheel. Another portion 78^b of this cam groove is off-set outwardly or toward the periphery of the mold wheel, and a third portion 78^c of this cam groove 90 is further off-set outwardly toward the periphery of the mold wheel. Those bottom ends folders 74 whose rollers rest in the portion 78^a of the cam groove will occupy fully 95 retracted positions where their outer edges are withdrawn inwardly past the bottoms of the mold pockets, as will be clear from Fig. 28 while the bottom folders whose rollers en- 100 gage the portion 78^b of the cam will be ex- 105 tended outwardly past the ends of the mold pockets and the outer edges of these bottom end folders will be substantially even with the periphery of the mold wheel; and the end folders whose roller engages the portion 78^c of the cam groove will be extended beyond the periphery of the mold wheel, as will be clear from Figure 28.

The cam 77 is mounted rotatably on the hub of the mold wheel in order that the latter may rotate independently of the cam, and means is provided for imparting a forward and rearward rotation to the cam at appropriate intervals. As shown, a sleeve 80 is mounted loosely on the mold wheel shaft 7, this sleeve having an arm 81 which is engaged between a pair of set screws 82 the latter being mounted in lugs formed on the cam, adjustment of these set screws serving to adjust the angular relationship between the cam and the sleeve 80. The latter has an actuating arm 83 bolted or otherwise fixed to it, this arm carrying a roller 84 which rides on a cam 86 and is held in contact therewith by a spring 87, the cam 86 being fixed on the continuously rotating main shaft 3 and shaped to impart to and fro rotary movements to the cam. These to and fro rotary movements of the cam serve to time the oper- 110 115 120 125

ations of the bottom end folders 74 in relation to the movements and the operative positions occupied by the mold wheel.

The bottom end folders 74 for the mold which is in position to receive the wrapper from the wrapper feeding means are retracted below the bottom or the inner wall of this mold, as will appear from Figure 4, the roller 79 which actuates these end folders 10 then occupying the section 78^a of the cam groove at a point adjacent to the incline of the groove which connects the section 78^a with the section 78^c. After a wrapper has been introduced into the mold by the grippers 60 and nipping plunger 62, and the grippers 60 have receded, but before the mold wheel advances, the cam 77 is rotated, through the action of the cam 86, to cause the roller 79 connected to the bottom end folders for 20 the mold in wrapper receiving position to pass from the section 78^a outwardly to the section 78^c of the cam groove, these bottom end folders being thereby forced outwardly past the opposite ends of the mold and they are 25 preferably forced outwardly to an extent sufficient to bring their outer edges beyond the periphery of the mold wheel. This outward movement of the bottom end folders takes place while the nipping plunger 62 30 is still contained in the mold and in consequence the first or bottom end folds *a* (Fig. 33) are made in the wrapper, these portions of the wrapper being folded against the respective ends of the nipping plunger which 35 serves as a former which defines the outline of the package. The nipping plunger is then elevated, thus withdrawing it from the mold, after which the mold and cam 77 advance a step, through the operation of the 40 Geneva movement, thereby bringing the mold containing the partly folded wrapper into a position to receive a charge of tobacco or other material. During this advance of the mold wheel and cam 77, the cam 77 operates to retain the bottom end folders 74 45 in their outwardly extended position, and the charge of tobacco or other material is introduced into the wrapper contained in the mold while these bottom end folders are in 50 this outward extended position as is shown in Fig. 4, the bottom end folders thus acting to hold the first or bottom end folds *a* of the wrapper in upright folded position and by arranging the bottom end folders so that 55 they project beyond the upper edges of these bottom folds of the wrapper and upwardly beyond the periphery of the mold wheel, they act as gates or walls which will prevent spilling of the tobacco or other material from 60 the ends of the mold pocket.

Different means may be employed for introducing the tobacco or other material into the wrappers. It is generally preferable to employ a press or similar packing device for 65 this purpose, especially when the wrappers

are being filled with granular tobacco, the press serving to compact the tobacco and to form it into a solid or firm body within the wrapper. The press which is shown in the present instance comprises a hopper 88 70 to which the tobacco or other material is supplied, a press member 89 the upper surface 90 of which covers and uncovers and thereby controls the delivery of the tobacco from the supply hopper, this press member being 75 mounted on and carried by an arm 91 which swings from a shaft 92, the upper surface 90 of the press member being concentric with the shaft 92 so that the surface 90 maintains contact with the lower edge of the hopper 80 during its swing. The lower edge of the press member 89 moves over a surface 93 which is also concentric with the shaft 92, it serving to remove the tobacco or other material that may lodge on the surface 93 and 85 to prevent leakage of tobacco between this surface and the lower edge of the member 89. The press member 89 has a relatively close fit with and operates between the pair of press side plates 94 which are relatively fixed 90 and may be supported on the cross member 95 mounted on the main frame. A discharge throat 96 is provided at the bottom of the press, the press member 89 while moving forwardly or toward the left in Figure 4 acting 95 to discharge the tobacco or other material into the discharge throat, and when the press member 89 has reached the limit of its forward stroke, that is, the position shown in Figure 4, its forward face is aligned with or forms a substantially unbroken continuation 100 of the wall 97 of the press throat. The press is provided with a lid member 98 which cooperates with the press member 89 and with the discharge throat 96 to form a passageway 105 through which the tobacco or material is conducted or directed to the mold wheel, and this lid also is movable into a position to close the discharge throat and thereby prevent leakage of the tobacco until the mold in 110 the mold wheel is ready to receive a charge. Preferably, and as shown, the lid member is fixed to a shaft 99 and the latter is rotatably mounted in the press side plates 94. The swing of the lid member in a direction away 115 from the press member 89 is limited by a boss 100 on the outer side of the lid member which is arranged to abut against a stop pin 101 the latter being fixed to one of the press side plates, these stops being properly positioned to determine the width of the passageway between the press members 89 and 98. The position of the lid member 98 is controlled by an arm 102 which is fixed to the 120 arm 91 which actuates the press member 89, the free end of the arm 102 acting on a crank 103 which is fixed to the lid supporting shaft 99, whereby when the press member 89 is retracted to uncover more or less the bottom 125 of the supply hopper 88 and thus permit a 130

supply of tobacco or other material to feed therefrom, the lid member 98 will swing toward the right in Fig. 4 under the action of a spring (not shown) until its lower edge 5 contacts with the wall 97 of the press discharge throat, the lid member then closing the press throat and preventing leakage or escape of tobacco or other material therefrom. The lid member is in such closed position during each advance of the mold wheel which carries a filled mold pocket from beneath the press and brings another empty mold pocket containing a wrapper into filling position beneath the press; and when the press member 10 89 is swung toward the left in Figure 4 to insure the deposit of all of the tobacco or other material fed from the supply hopper into the press discharge throat, the lid member is swung toward the left in that figure until 15 arrested by the stops 100 and 101, the lid member being shown in this position in Fig. 4. When the press member 89 and lid member 98 are in the positions shown in Fig. 4, a passageway is formed through which a 20 plunger 104 may reciprocate, this plunger serving, when moved downwardly, to transfer the tobacco or material from the press into the mold pocket and to pack it in the partly folded wrapper therein, and when 25 the plunger is moved upwardly or retracted, the lid member 98 is unobstructed so that it may close the press throat. The plunger 104 may be operated from a rock shaft 105 which is journaled in the side members 1 of the 30 frame, this shaft having a plunger actuating arm 106 thereon. The construction and operation of the press may be substantially the same as that shown and described in the patent hereinbefore referred to. The arm 35 91 which operates the press members 89 and 98 may be actuated, while the mold wheel is being advanced through each step, by an arm 107 fixed on the shaft exteriorly of the frame and carrying a roller 108 which engages in a suitably shaped cam groove formed in the outer face of a wheel 109, the latter being fixed on the main shaft 3. The plunger 40 104 may be reciprocated, while the mold wheel is at rest and one of the pockets therein 45 is in charge receiving position, by a crank 110 which is fixed on an end of the shaft 105, this crank being connected by a link 111 to a lever 112 which may be pivoted on the pin 113, this lever having a roller which rides 50 in a cam groove formed in the inner side of the wheel 109, substantially as shown in the patent hereinbefore referred to.

During the advance of the mold wheel which brings an empty but partially folded wrapper from the wrapper applying position to filling position, and also while this pocket in the mold wheel occupies filling position, the bottom end folders 74 are held in their extreme outer positions by reason of 55 the engagement of the roller 79 connected to

these bottom end folders with the section 78^a of the cam 78, this section of the cam 78 having the greatest radius. These bottom end folders will therefore not only serve to hold the bottom end folds of the wrapper in proper 60 form during the transfer of the partially folded wrapper from the wrapper applying position to the filling position, but they will also serve as gates or walls at the ends of the mold during filling thereof and they will 65 thus prevent spilling or leakage of the tobacco or other material at these points. The next step in the advance of the mold wheel brings the roller 79 for these end folders into the portion 78^b of the cam 78, this section of the cam being of intermediate radius, and the end folders will in consequence be 70 partly retracted or moved inwardly so that their outer edges are substantially even with the outer periphery of the mold wheel. 75

Each partially folded wrapper filled with the tobacco or other contents, after it has been removed from the press or packer is acted on by a pair of top folders 114 and 115, these being shown particularly in Figures 4, 10, 11 80 and 15 to 18 inclusive. The folder 114 serves to lay one end of the wrapper over the top of the charge contained therein thus forming the fold *b* as shown in Fig. 34, and the folder 115 serves to lay the other end of the wrapper over the charge contained therein and over the fold *b*, thus producing the top fold *c* as shown in Fig. 35. These folders operate in close proximity to the periphery of the mold wheel and concentrically thereof. The folder 114 is carried on an arm 116 the hub 117 of which is mounted to rock loosely on the mold wheel shaft 7 and the lower end of this arm below the shaft 7 is operatively connected to a fork 118 which straddles the continuously revolving main shaft 3 and carries a roller 119 which cooperates with a cam 120, the latter being fixed on the shaft 3. A tension spring 121 attached to the lower end of the arm 112 acts to hold the roller 119 in contact with the periphery of the cam 120. The cam 120 is so shaped and set as to cause the folder 114 to swing either to the position shown in Figure 10, in which position it is immediately adjacent to the mold which is in 90 filling position beneath the press, the folder 114 then serving to back up the forward end of the wrapper which projects beyond the mold and thus prevent spilling or leakage of the tobacco during the filling operation, and to cause this folder 114 to be moved during the following advance of the mold wheel but at a retarded rate so that the outwardly or upwardly projecting forward end of the wrapper will pass under this folder, and as the mold wheel is completing its advance, the folder 114 overtakes the outwardly or upwardly projecting rear end of the wrapper and as the folder 114 completes its motion in 95 this direction it lays this rear projecting end 100

of the wrapper over the top of the package thus making the top fold *b* in the manner shown diagrammatically in Figure 15 and as represented in Figure 34.

5 The top folder 115 is carried by an arm 122, the hub 123 of which is also loosely mounted on the mold wheel shaft 7, the lower end of this arm below the shaft 7 being operatively connected to a fork 124 which straddles the continuously running main shaft 3 and carries a roller 125 which cooperates with the cam 126, the latter being fixed on the shaft 3. A spring 127 acts on the arm 122 to hold the roller 125 in contact with the periphery of the cam 126. The cam 126 is so shaped and set that when a partially folded and filled wrapper has been advanced a step from the filling position, an edge of the top folder 115 will be positioned immediately adjacent to the forward edge of the mold, the folder 115 being shown in this position in Figs. 10 and 15, and after the folder 114 has advanced and laid over the rear end of the wrapper to make the top fold *b*, the folder 115 moves in a direction 10 to carry it over the adjacent mold containing the partially folded and filled wrapper. During this movement of the folder 115, the folder 114 recedes, and this movement of the folder 115 serves to lay the forward end of the 15 wrapper over the top of the charge contained therein, in the manner shown diagrammatically in Figs. 16 and 17, thus forming the top fold *c* as shown in Fig. 35. The movement of the folder 115 in the direction which makes the fold *c* continues until this folder overlies both folds *b* and *c* and its edge is about even with the rear edge of the mold pocket.

After the folders 114 and 115 have operated to make the top folds *b* and *c*, a tucker 128 40 operates to tuck the extension of the fold *c* which projects rearwardly beyond the rear edge of the package downwardly or inwardly so that it lies flatwise against the narrow rear side of the package, thus making the fold 45 *d* represented in Fig. 36. The operation of the tucker 128 to make the fold *d* is permitted by the rear mold lid 17 which is retracted while this fold is being made against the rear side of the package by operation of the lever 22 which causes the pin 21 thereon to depress the actuating projection 20 of the corresponding mold lid which in this position of the mold wheel, registers with it as shown in Figures 12 and 13, it being understood that the lid 17 is closed 50 during the folding operations of the folders 114 and 115. Figure 18 represents diagrammatically the manner in which the mold lid 17 is retracted to expose the rear side of the package in the mold cavity and the manner in which the tucker 128 moves downwardly or inwardly to lay the end of the wrapper against the rear side thereof and thus produce the fold *d*. The folder 115 overlies the package during this tucking operation and

it thereby serves to retain the package in proper form and position in the mold pocket and maintains the previously made folds *b* and *c* in proper form.

The tucker is shown particularly in Figures 12, 13 and 14, it consisting of a finger and blade which is fixed to the free end of an arm 129 the latter being fixed on a shaft 130 journalled in a bracket 131, the axis of the shaft 130 being located approximately coincident with the periphery of the mold wheel so that the tucker, in acting on the wrapper to make the fold *d* will move in substantial parallelism with the plane of the rear side of the package. The supporting bracket 131 for the tucker may be attached by a clamp or other suitable means to a rod 132 which extends across and connects the side members 1 of the frame, and the bracket may be steadied by providing a saddle 133 thereon to fit against the shaft 105. The tucker carrying shaft 130 may be rocked to swing the tucker to and from operative position at appropriate intervals by a crank arm 134 which is fixed to the shaft 130 and is connected by a link 135 to a fork 136 which straddles the continuously running main shaft 3 and carries a roller 137 which rides on the periphery of an appropriately shaped cam 138 the latter being fixed on the shaft 3. 70

The next step in the advance of the mold wheel brings the package which has been folded and tucked in the manner just described into position for folding and closing of its ends. During the transfer of the package from top folding and tucking to end folding position, the roller 79 connected to the bottom end folders 74 for the respective mold reach the innermost section 78^a of the cam 78, thereby causing these bottom end folders to be retracted or those inwardly to or below the bottom of the mold pocket, the bottom end folders appearing near the top of Fig. 25 being shown in this retracted position. When the bottom end folders are thus retracted, the unfolded ends of the wrapper are exposed or made accessible for the operation of the end folders thereon. 100

The package end folders are shown particularly in Figures 19 to 23 inclusive. A 115 pair of these end folders 139 is provided to act on each of the two ends of the package, these end folders comprising fingers which are fixed to shafts 140 which are journalled in a bracket 141 and are connected by gear segments 142 or other suitable means whereby these shafts and in consequence the end folding fingers fixed thereon will swing in unison at both ends of the mold pocket, the end folding fingers fixed to one shaft moving 120 in opposite direction to those fixed to the other shaft. The bracket 141 which supports the end folders in position adjacent to the periphery of the mold wheel may be fixed by a clamp or other suitable means to the 130

rigid cross rod 132 of the frame and this bracket may be provided with a saddle 143 to bear against the shaft 105 whereby the bracket 141 is held steady. The shafts 140 are so located beyond the periphery of the mold wheel as to cause the operative ends of the fingers 139 to swing from the relatively retracted position shown in Fig. 20 inwardly to the operative position shown in Figure 21, and as these fingers swing into the operative position they engage the forward and rear edges of the wrapper which project laterally beyond the sides of the mold wheel and then fold these portions of the wrapper inwardly against the respective ends of the package thus making the end folds *e* and *f* as shown in Fig. 37. During this end folding operation of the fingers 139, the bottom end folders 74 are retracted as will be clear from Figure 21 and hence the folds *e* and *f* are made directly against the previously made bottom end fold *a*.

In order to make a relatively sharp bend or crease between the end folds *e* and *f* and the top folds *b* and *c* and at the same time avoid leakage of tobacco or other material from the package during this folding operation, means is provided which holds the top folds *b* and *c* in proper folded position and confines the package in proper form within the mold pocket. Such means comprises preferably a guard 143 which is shaped to conform closely to the peripheral curvature of the mold wheel and is positioned to lie against the periphery of the mold wheel for a suitable distance beyond the top folders 114 and 115, this guard serving in effect as a cover for the mold pockets while the end folding operations are being performed. Preferably the guard is held in direct contact with the periphery of the mold wheel while the latter is at rest and the end folding operations are taking place but is retracted or disengaged from the mold wheel during the periods the mold wheel is being advanced. For this purpose, the guard may be fixed on a rock shaft 144 which is mounted in relatively fixed bearings in the side frame members 1, and the shaft 144 may be rocked preparatory to each advance of the mold wheel to retract the guard therefrom by an arm 145 which is fixed to said shaft and carries a roller 146 which bears on a suitably shaped cam 147, the latter being fixed on the continuously running main shaft 3. A tension spring 148 acts on the arm 145 to hold the roller 146 in contact with said cam and to press the guard against the periphery of the mold wheel except when the guard is retracted during the advancing movements of the mold wheel.

The end folders 139 may be operated by an arm 149 fixed to one of the shafts 140, this arm being connected by a rod 150 to an arm 151, the latter being loosely mounted on a

shaft such as the shaft 144 and the arm 151 may be connected to another arm 152 which carries a roller 153, the latter riding on a cam 154 fixed on the continuously running main shaft 3. A spring 151^a preferably acts to hold the cam 153 in contact with the cam 154 and to swing the folders 139 on their operating strokes.

After the side end folds *e* and *f* have been made, the final or top end fold *g* is made substantially as shown in Fig. 28, this fold being made against the previously made folds *a*, *e* and *f*. The top end folder preferably acts to make the top end folds *g* immediately after the folders 139 have operated to make the end folds *e* and *f* preferably before the mold makes its next advance. As shown in the present instance a top end folder 155 is employed which comprises a pair of plates 156 (Fig. 23) which are rigidly held in spaced relation and are adapted to straddle the peripheral portion of the mold wheel so that when this folder is moved inwardly or toward the center of the mold wheel, the plates 156 will engage the top ends of the package which project laterally beyond the opposite sides of the mold wheel, as appears in Figure 23 and will bend or fold these portions of the wrapper downwardly or inwardly against the ends of the respective package in the mold pocket. The top end folder 155 operates after the folders 139 have been retracted, as will be clear from Fig. 22 although the folder 155 will be retracted while the folders 139 are operated, as will be clear from Fig. 21. The top end folder 155 may be operated at appropriate intervals by an arm 157 which may serve to carry this folder, this arm being fixed to a shaft 158 which may be journaled in the side frame members 1, the shaft 158 being rocked by an arm 159 which carries a roller 160, the latter bearing on a suitably shaped cam 161 fixed on the main shaft 3.

Means is preferably provided for indenting or countersinking the folded ends of the packages in order to lock the end folds in folded position and thus prevent or minimize leakage of the tobacco or other material from the packages. The indenting or countersinking means is preferably arranged to act on each package after it has been advanced to the next position by the rotation of the mold wheel. The indenting or countersinking means is shown particularly in Figures 24 to 27 inclusive, it comprising a pair of countersinks 162 having rods 163 connected thereto, the latter being mounted to reciprocate in guides 164 which are supported from the frame side members at opposite sides of the mold wheel, the countersinks being movable slightly into and out of the ends of a mold pocket which is in register with them for each operating position of the mold wheel. The forcing of these countersinks into the folded ends of the package contained in the

mold pocket causes the folded ends of the package to be indented, thus densifying the charge of tobacco or other material contained in the wrapper, and the countersinks also set 5 to crease or bend the end folds sharply on the lines where they join the sides of the wrapper, thereby imparting a permanent set to the end folds which tends to lock or retain them in closed or folded position. The densifying of the contents of the wrapper and 10 the sharp creasing of the end folds are facilitated by the confinement of the package during this operation within the mold pocket by the guard 143 which at this time is pressed 15 into contact with the periphery of the mold wheel. In order to prevent springing open of the end folds of the wrapper while the package is being transferred from the end folding position to the countersinking position, 20 guards 165 are mounted in fixed positions at opposite sides of the mold wheel and extend between the end folders and the countersinks. The countersinks may be forced inwardly 25 to indent or countersink the package and then retracted, during each pause in the rotation of the mold wheel, by any suitable means such for example as that shown and described in the patent hereinbefore referred to, cranks 166 being shown connected to the outer ends 30 of the rods 163 and supported on shafts 167 mounted in brackets 168, these shafts also having other cranks 169 fixed thereto and connected by links 170 to cranks 171 which are fixed on the cross shaft 44 near its respective ends, and the shaft 44 is rocked to simultaneously actuate both cranks by a suitably shaped cam 172 fixed on the shaft 26 and cooperative with an extension 171^a on one of the cranks whereby one complete operation of both countersinks will take place 35 during each pause of the mold wheel.

After the ends of the packages have been indented by the countersinks, the following successive movements of the mold wheel advances the packages to the discharge point. 45 The packages may be discharged or removed from the mold wheel in any suitable way. In the present instance the packages are ejected endwise of the respective mold wheel 50 pockets by an ejector blade 173 which is mounted to reciprocate in a relatively fixed guide 174, the guide being mounted suitably so as to be in alinement with a mold wheel pocket each time the latter has completed a step in its advance. The blade 173 makes a forward or package ejecting stroke 55 and a return stroke during each pause in the rotation of the mold wheel, it being operatively connected in the present instance to an arm 175 which is fixed to a rock shaft 176 the latter being connected by gear segments 177 to an arm 178 and the latter having a roller or projection 179 thereon, as shown 60 in the patent hereinbefore described, which cooperates with a suitably shaped cam groove

formed in wheel 113. An endless flexible conveyer 180 may be provided for conducting the discharged packages to a table or other point, this conveyer being arranged at the discharge side of the mold wheel so that it will receive the packages discharged therefrom and it may be driven from a pulley 181 over which its lower end passes, it being understood that its opposite end will pass over a similar idler pulley. The pulley 181 may be 75 driven from a shaft 182 which serves to support it, and the shaft 182 may be driven by a sprocket wheel 183 fixed thereon and a chain 184 which passes around said sprocket wheel and a sprocket wheel 185 which is fixed on the continuously revolving main shaft 3. In order to prevent accidental dropping of any 80 of the packages from the mold pockets in the mold wheel while these packages are passing around the under side, a supplementary 85 guard 186 may be fitted around the under side of the mold wheel in close proximity to the periphery thereof and extended from the guard 143 to the discharge point.

The operation of the machine is as follows. 90 A row of paper or other wrappers which may be fed manually or otherwise to the feed trough 30 is advanced by the respective hooks 32 of the travelling conveyer 31, this conveyer moving continuously in a direction 95 which will advance the wrappers toward the mold wheel. As each wrapper approaches the stops 43 on the wrapper supporting arms 42, the registering fingers 47 swing forwardly so that they engage the rear edge of this 100 wrapper and complete its advance so that its forward edge is registered against the stops 43. The advance of the wrapper by the registering fingers 47 frees its rear edge from the hook 32 so that this hook may pass with 105 the conveyer around the sprocket 34 without injuring the wrapper.

When the wrapper has reached the position described, the nipping plunger 62 and the grippers 60 descend or swing forwardly 110 toward the wrapper supporting arms 42 and the paper is gripped momentarily between the grippers 60 and the arms 42. The wrapper supporting arms 42 then descend, releasing the wrapper, and the wrapper is carried into the mold pocket in the mold wheel which occupies wrapper receiving position. The wrapper is pressed into the mold pocket by the nipping plunger 62 so that the wrapper lies against the bottom and radial sides of the mold pocket, and the lip 63 on the nipping plunger during this operation creases the wrapper sharply around the forward overhanging lip 29 of the mold pocket. The grippers 60 engage the ends of the wrapper which 115 project beyond the opposite sides of the mold wheel and thus assist in carrying the wrapper into the mold pocket and folding it to form the bottom and two sides thereof. The grippers 60 then recede and the bottom end fold- 120

ers 74 move radially outwardly, they engaging the bottom portions of the wrapper which project beyond the opposite sides of the mold wheel and bending them against the ends of the nipping plunger 62 to form the bottom end folds *a* as is shown in Fig. 33. The bottom end folders 74 remain in their outer positions but the nipping plunger 62 rises, thus withdrawing it from the wrapper contained in the mold pocket. After the nipping plunger has been withdrawn, the mold wheel advances a step, the wrapper just applied to the mold pocket being brought into filling position beneath the press. During the advance of the mold wheel, the press plunger 104 is in the elevated position, the press member 89 is retracted toward the right or in the opposite position to that shown in Fig. 4 and the press lid 98 is swung across the discharge throat 96 of the press so that the lower edge of the press lid engages the surface 97 and thus closes the discharge throat of the press to prevent discharge of tobacco or other material from the press until the wrapper is properly positioned to receive a charge. After the mold wheel has completed its advance and the partly formed wrapper has been brought into filling position beneath the press, the press member 89 and press lid 98 move into the position shown in Fig. 4, a charge of material being thus fed into the press throat 96 and thence into the open wrapper contained in the mold pocket positioned beneath it, and while the mold wheel is still at rest, the press plunger 104 descends through the press and into the mold thereby pressing the charge of tobacco solidly or firmly within the wrapper.

After the charge of tobacco or other material has been pressed into the partly folded wrapper, the mold wheel makes another advance, thus bringing this wrapper into position to be operated on by the top folders 114 and 115. During this advance of the mold wheel, the free ends of the wrapper which project outwardly beyond the periphery of the mold wheel pass freely beneath the folder 114 after which the folder 114 swings in the direction in which the mold wheel is advancing, and during the final portion of the advance of the mold wheel, the folder 114 overtakes the rear upstanding end of the wrapper and folds it over the top of the package in the manner represented diagrammatically in Figure 15, thus making the first top fold *b* as shown in Fig. 34. After the mold wheel has come to rest, the top folder 115 swings over the package contained in the mold pocket and in so doing folds or lays the forward projecting end of the wrapper over the top of the package and over the previously laid fold *b*, in the manner shown diagrammatically in Fig. 16 and making the second top fold *c* as shown in Fig. 35. During the first part of the advance of the top folder 115

to make the fold *c*, the top folder 114 remains in the position which it reached in making the top fold *b*, it thereby holding the first top fold *b* in position to be overlapped by the second top fold *c* and after the second fold has commenced over the first top fold *b* the top folder 114 recedes or returns to its former or initial position while the former 115 continues its advance thus completing the lapping and laying of the second top fold *c*, as represented in Fig. 14. While the top folder 115 overlies the entire upper side of the package, the tucker 128 swings toward the mold wheel and the mold lid 17 at the same time is retracted. The tucker thus engages the free end of the wrapper which extends beyond the rear edge of the package and folds it against the rear side of the package which is exposed or made accessible by retraction of the mold lid 17, this operation being shown diagrammatically in Fig. 18 and the last top fold *b* made by this operation being shown in Fig. 36.

After the folds *b*, *c* and *d* are made, the mold wheel advances another step thereby bringing the package into the end folding position. When the package reaches this position, the bottom end folders 74 have been retracted, and after the mold wheel has come to rest, the guard 143 is pressed against the circumference of the mold wheel and thereby confines the package at its outer side. The end folders 139 then swing into position at the ends of the package thereby producing the folds *e* and *f* therein as shown in Fig. 37 and after the end folders 139 have performed this operation and have been retracted, the top end folder 155 swings inwardly producing the last end fold *g* as shown in Fig. 38.

After the end folds just described have been made, the mold wheel again advances, thereby bringing the folded ends of the package into alignment between the countersinks 162, and after the mold wheel has come to rest, these countersinks move inwardly into the folded ends of the package thereby compacting the charge therein and also creasing the end folds on the lines where they join the sides of the package thereby imparting to these folds a tendency to remain in closed position and to lock the folds in closed position. The subsequent advancing movements of the mold wheel eventually bring each package into register with the ejector blade 173, and as the mold wheel comes to rest, this blade makes a forward and return stroke thereby ejecting the finished package from its mold pocket onto the conveyor belt 180 which serves to convey the packages from the machine to a table or other desired point.

By making the bottom end folds in the wrapper immediately after the wrapper is introduced into the mold pocket, the wrapper is immediately prepared to receive its charge of tobacco or other material from the

press, and while receiving the charge, the bottom end folds of the wrapper, which are turned upwardly, serve as walls which confine the tobacco and thus prevent spilling of the same from the ends of the wrapper. These bottom end folds are firmly held in upstanding or folded position during the introduction of the charge, by the bottom end folders which are then in extended position, and hence the bottom end folds are capable of sustaining the compression exerted on the charge by the press plunger, with the result that the charge is packed solidly in the wrapper. During the introduction of the charge into the wrapper, the relatively longer end of the wrapper which projects from the forward side of the mold is sustained by the folder which makes the first top fold of the wrapper, and this end of the wrapper is thus held in a position whereby it will prevent spilling and consequent loss of tobacco at this side of the mold.

By laying the relatively shorter end of the wrapper, which projects from the rear side of the mold, over the top of the charge contained in the wrapper and then laying the other relatively larger end of the wrapper over the top of the charge and the first made top fold and turning the extremity of this end of the wrapper against the rear side of the package, a tight drawing of the wrapper around the charge therein is attained whereby the charge is held in a solid or firm condition. During this operation, the ends of the package are confined by the bottom end folders which are still in extended position, and hence distortion of the bottom end folds previously made or escape of tobacco from the ends of the package is avoided.

The remaining end folds are made to close the ends of the package while the sides and top of the package are confined against expansion or distortion, and hence these end folds may be made solidly against the compact or compressed charge, and by indenting the folded ends of the package while the latter is maintained under compression or is confined at its sides and top, the charge within the wrapper is further densified and the end folds are countersunk so that they become locked in folded position.

The present invention thus enables packages to be made which are solid or firm and are thus capable of retaining their original form, and sifting or leakage of the tobacco or other contents therefrom is minimized or avoided.

I claim as my invention:—

1. In a packaging machine, the combination of a mold, means for feeding a wrapper into a position adjacent to the mold, means to receive the wrapper from the feeding means and operative to further feed and thus register it relatively to the mold, and means

operative upon the registered wrapper to introduce it into the mold. 65

2. In a packaging machine, the combination of a mold, means to receive a wrapper and having registering stops thereon for registering the wrapper relatively to the mold, 70 cooperating members for moving the wrapper into registered position against said stops and means operative upon the wrapper to introduce it into the mold, said wrapper receiving means being movable toward the mold during the introduction of the 75 wrapper therein.

3. In a packaging machine, the combination of a mold, feeding means for advancing a wrapper to a position adjacent to the mold, 80 registering means for positioning the wrapper relatively to the mold, said registering means including devices operative to advance the wrapper independently of the feeding means and registering stops which arrest the 85 advance of the wrapper by said devices, and means operative upon the registered wrapper to introduce it into the mold.

4. In a packaging machine, the combination of a mold, a pair of wrapper supporting 90 arms movable past the ends of the mold and having wrapper-registering stops thereon, fingers movable toward said stops for registering a wrapper therewith and means operative upon the wrapper, while the wrapper 95 supporting arms are moving past the ends of the mold, to introduce the wrapper into the mold.

5. In a packaging machine, the combination of a rotatable mold wheel provided with 100 a mold having an open top at the periphery of the wheel and open ends at the sides of the wheel, a plunger operative to carry a wrapper into the open top of the mold so that portions of the wrapper project from the open 105 ends thereof, filling means for introducing a charge into the wrapper in the mold when rotation of the mold wheel brings the wrapper and mold opposite to such filling means, wrapper folding means arranged to operate 110 on the wrapper after further rotation of the wheel has removed the wrapper and mold from the filling means, end folders movable transversely across the ends of the mold in a direction toward and from the periphery of 115 the wheel, and means for moving said end folders outwardly beyond the periphery of the wheel to fold the projecting ends of the wrapper against said plunger and for holding said end folders outwardly beyond the periphery 120 of the wheel during rotation of the wheel and until after the filling means has introduced a charge into the wrapper and for partially 125 retracting the end folders inwardly preparatory to the operation of the wrapper folding means on the wrapper.

6. In a packaging machine, the combination of a mold, means for supporting a wrapper

- and movable toward the mold to conduct the wrapper thereto, and means for introducing the wrapper into the mold including a plunger which enters and carries the wrapper into the mold and independently movable grippers which grip the wrapper between them and said wrapper supporting means during the movement of the latter toward the mold.
7. In a packaging machine, the combination of a mold, having open ends, a plunger movable into the mold to carry a wrapper therein and partially fold it, and supplementary members arranged at opposite sides of the plunger and movable therewith toward the mold to engage portions of the wrapper which project from the respective open ends of the mold, said supplemental members being capable of retraction while the plunger remains in the mold.
- 10 8. In a packaging machine, the combination of a mold having open ends, a plunger and cooperating members operative to carry a wrapper into the mold whereby portions of the wrapper project from the open ends thereof, said members being capable of retraction while the plunger remains in the mold, and end folders operative to fold said projecting portions upwardly from the bottom of the mold and against the ends of the plunger therein.
- 15 9. In a packaging machine, the combination of a mold having longitudinal lips which overhang the cavity thereof, and means including a plunger for introducing a wrapper into the mold, the plunger having a lip along one of its longitudinal edges which is adapted to overlap one of the lips on the mold and to sharply nip the portion of the wrapper between it and said lip of the mold.
- 20 10. In a packaging machine, the combination of a mold having open ends and movable from a wrapper-receiving position to a filling position, a plunger and cooperative members movable in unison with and also independently thereof for introducing a wrapper into the mold while the latter is in wrapper-receiving position whereby portions of the wrapper project through the open ends of the mold, end folders operative upon said projecting portions of the wrapper to fold them upward, and inwardly against the ends of the plunger therein while said members are retracted, means for maintaining the end folders in position to sustain said folded portions of the wrapper while the mold is moved from wrapper-receiving to filling position, and means for introducing a charge of material into the wrapper while its end portions are maintained in folded position.
- 25 11. In a packaging machine, the combination of an open-top mold adapted to contain a partly-folded wrapper whereby the ends of the wrapper project beyond the top of the mold, means for introducing a charge of material into the wrapper through the open
- top of the mold, and a folder for one of the projecting ends of the wrapper, said folder occupying a position in a plane above the top of the mold to support one of said projecting ends of the wrapper while the charge is being introduced therein.
- 30 12. In a packaging machine, the combination of a mold wheel having in its periphery an open-top mold adapted to receive a wrapper with its ends projecting from its top and beyond the periphery of the mold wheel, means for introducing a charge of material into the wrapper contained in the mold, folders movable in a direction peripherally of the mold wheel and operative to successively lay the wrapper ends over the top of the charge, one of said folders occupying a position to support one of the projecting ends of the wrapper while the charge is being introduced therein and a tucker operative to lay the extremity of the last-folded end of the wrapper against a side of the package.
- 35 13. In a packaging machine, the combination of a mold wheel having a mold therein open at the periphery of the wheel, means for introducing a wrapper into the mold whereby the ends of the wrapper project from the mold and beyond the periphery of the wheel, means for introducing a charge of material into the wrapper in the mold, and a pair of folders mounted to swing concentrically with respect to the periphery of the mold wheel, one of said folders being operative to support one of the projecting ends of the wrapper while the charge is being introduced therein, and the pair of folders being operative to fold the ends of the wrapper successively over the charge contained in the wrapper.
- 40 14. In a packaging machine, the combination of a mold wheel having a mold pocket in its periphery adapted to contain a wrapper the ends of which project from the periphery of the wheel, means for filling the wrapper, means for imparting a step-by-step advance to the mold wheel, a pair of folders for laying the projecting ends of the wrapper over the top of the package in the mold, and means for actuating said folders whereby one of them operates during the advance of the mold from filling position, to fold one end of the wrapper and the other folder operates while the mold is at rest to fold the other end of the wrapper.
- 45 15. In a packaging machine, the combination of a mold wheel having a mold pocket in its periphery to contain a wrapper the ends of which project from the periphery of the wheel, a pair of folders mounted to swing concentrically of the periphery of the wheel, and means for swinging said folders relatively to the mold wheel to cause them to successively lay the respective ends of the wrapper over the top of the package.
- 50 16. In a packaging machine, the combina-

tion of an open-top mold adapted to contain a wrapper the ends of which project from the open top of the mold, folders relatively movable over the top of the mold and operative to lay the projecting ends of the wrapper successively over the top of the package, one of said folders overlaying the package after its folding operation has been completed, and a tucker operative to lay the extremity of the last-made top fold against the adjacent side of the package while said folder overlies the package.

17. In a packaging machine, the combination of a rotatable mold wheel having a mold pocket which is open at the periphery and the opposite sides of the wheel, a plunger for introducing a wrapper into the mold and for partially folding it whereby its ends project from the periphery of the wheel, members cooperative with said plunger for shaping the ends of the wrapper which project from the opposite sides of the wheel and capable of retraction independently of the plunger, folders carried by the wheel and operative to fold portions of the wrapper which project from the sides of the wheel outwardly toward the periphery thereof and against said plunger after retraction of said members, means for filling the wrapper while the portions of the wrapper at the sides of the wheel are held in outwardly-folded position by said end folders, and means operative to lay the projecting ends of the wrapper over the top of the package while the end folders hold the portions of the wrapper at the sides of the wheel in outwardly-folded position.

18. In a packaging machine, the combination of a rotatable mold wheel having a series of mold pockets in its periphery, said pockets being open at the sides of the wheel, a plunger operative upon the intermediate portion of the wrapper to introduce it into the mold, cooperative members operative upon portions of the wrappers which project from the open ends of the mold, said members being capable of retraction while the plunger remains within the wrapper, folders movable radially of the wheel past the open ends of the respective mold pockets to produce bottom end folds in said projecting portions of the wrappers while the plunger is within the respective wrapper and said members are retracted, and a cam cooperative with said folders for controlling their movements.

19. In a packaging machine, the combination of a rotatable mold wheel having a series

of mold pockets in its periphery, said pockets being open at the sides of the wheel, pairs of folders movable radially past the open sides of the respective mold pockets, and a cam cooperative with said folders for actuating them, said cam being coaxial with but rotatable independently of the rotation of the mold wheel.

20. In a packaging machine, the combination of a rotatable mold wheel carrying a mold having open ends and adapted to contain a wrapper portions of which project from the open ends of the mold, bottom end folders carried by the mold wheel and operative to make bottom folds in the projecting portions of the wrapper and having means for moving them to and from operative position, side-end folders operative upon said projecting portion of the wrapper while the bottom end folders are in inoperative position, and top end folders operative subsequently to the operation of the side end folders.

21. In a packaging machine, the combination of a rotatable mold wheel carrying an open-top, open-end mold adapted to contain a wrapper portions of which project from the open ends of the mold and the ends of which project from the open top of the mold and beyond the periphery of the mold wheel, folders carried by the mold wheel and movable into operative position for forming bottom end folds in said projecting portions of the wrapper and subsequently movable into inoperative position, means for filling the wrapper while said folders sustain the bottom end folds, top folders movable relatively to the mold wheel in a direction peripherally thereof and operative to lay the projecting ends of the wrapper over the package while said bottom end folds are sustained by said first-mentioned folders, a tucker operative to lay the extremity of an end of the wrapper against a side of the package while the bottom end fold is sustained by said first-mentioned folders, side-end folders and top-end folders operative to fold the side end and top end portions of the wrapper against the ends of the package while the first-mentioned folders are in inoperative position, and countersinks operative to indent the folded ends of the packages.

In testimony whereof I have hereunto set my hand.

LOUIS FISCHER.
